ALBERT HARRISON DE VOE, OF WESTFIELD, NEW JERSEY, ASSIGNEE TO THE SINGER
MANUFACTURING COMPANY, A CORPORATION OF NEW JERSEY.

SEWING-MACHINE LOOP-TAKER MECHANISM.

1,256,880.

Specification of Letters Patent. Patented Feb. 19, 1918.

Application filed October 6, 1913, Serial No. 793,535. Renewed August 3, 1916. Serial No. 112,022.

To all whom it may concern:

Be it known that I, ALBERT H. DE VOE, a citizen of the United States, residing at Westfield, in the county of Union and State 5 of New Jersey, have invented certain new and useful Improvements in Sewing-Machine Loop-Taker Mechanisms, of which the following is a specification, reference being had therein to the accompanying drawings.

10 This invention has for its object to provide a chain-stitch sewing machine with an effective form of looper and with actuating mechanism therefor which shall permit the arrangement of the needles in a line at right angles with the direction of feed for producing a series of parallel independent seams and shall cause the loopers to coöperate with the needles with the least possible strain upon the thread.

20 With machines fitted for different uses, involving variations in the spacing apart of the needles and loopers and other differences, it has been common to construct special loopers in a large variety of different forms. One feature of the present invention 25 consists in the construction of the loopers in separate shank and blade portions, the former being uniform for various forms of blade portions adapted to be secured thereto.

30 In the preferred embodiment of the improvement the loopers are set at an acute angle with the direction of feed upon a common looper-carrier mounted to slide and oscillate upon a fulerum at right angles with 35 the direction of feed, the movements of the carrier being such as to impart to the loopers movements in elliptical paths of which the major axes are substantially parallel with the looper-blades and thus at an acute angle with the direction of feed. The looper-carrier preferably derives its operative movements from an inclined crank having its axis arranged in non-intersecting relation with the axis of an actuating shaft 45 disposed at right angles with the direction of feed and embraced by a strap at one end of a pitman-lever whose opposite end has a pivotal connection with a rigid lateral arm of the looper-carrier, said strap sustaining a 50 rigid eyed thread-controlling arm coöperating with an eyed guide-element rigidly sustained by the looper-carrier through which the looper thread is led in a substantially direct line from one or more stationary

guide-eyes interposed between it and the 55 thread supply.

Means are preferably provided for simultaneously locking the actuating shaft from rotation and shifting the looper-carrier supporting fulerum to cause the looper-carrier 60 to recede from normal position in retraction of the loopers from normal relation with the needles for purposes of threading.

In the drawings, Figure 1 is a perspective view of a double-chain stitch sewing machine 65 of the wellknown Singer type embodying the present improvement; the frame being indicated in dotted lines. Fig. 2 is a front end view of the same partly in section. Fig. 3 is a perspective view of the looper mechanism, detached, and Fig. 4 a similar view 70 representing the main-shaft with its looper-actuating crank and locking means. Figs. 5, 6 and 7 are detail views of a portion of the main-shaft and looper-actuating crank. 75 Figs. 8, 9 and 10 are respectively plan, side and rear end views of the looper. Fig. 11 is a diagrammatic view representing the path of movement of one of the loopers with respect to the needle with which it coöperates. Fig. 12 is a perspective view representing the forward or beak portion of a 80 looper-blade of alternative form.

As represented, the machine is constructed with the usual base 1 from which rises the 85 standard 2 sustaining the overhanging tubular arm 3 terminating in the hollow head 4. Within suitable bearings of the base 1 is disposed the main-shaft 5 extending longitudinally thereof and provided in its forward portion with the inclined looper-actuating crank 6 and in its rearward portion with 90 the needle-actuating ball-crank 7. The main-shaft is provided at its rearward end with the usual grooved belt-pulley 8 provided 95 with the balance-wheel 9.

The crank 7 is embraced by the strap 10 at the lower end of the pitman 11 whose opposite end is connected by means of the stud 12 with the lateral crank-arm 13 fixed upon 100 the rearward end of the needle-actuating rock-shaft 14 journaled within and longitudinally of the overhanging arm 3 and carrying at its forward end the crank-arm 15 provided with the stud 16 which is embraced by the apertured boss at the upper end of the link 17 having a similar boss at its opposite end embracing the stud-pin 18 of the 105

collar 19 secured upon the reciprocating needle-bar 20 journaled in the bracket-arm head 4 in the usual manner. As represented in the drawings, the needle-bar carries at 5 its lower end the multiple needle-clamp 21 provided with the usual sockets in which are secured by means of set-screws 22 the shanks of the needles 23 arranged in a line cross-wise of the direction of feed and substantially parallel with the main-shaft 5.

Coöperating with each of the needles is a looper which is shown in the drawings constructed in separable blade and shank portions, the blade 24 being provided at its forward end with the usual thread-eye 25 and at its rearward end or heel with the depending extension 26 formed with a transverse groove 27. The shank portion 28 is in the form of a flat plate having upon one face 15 the transverse tongue or rib 29 fitted to the groove 27 of the blade-extension 26 and a lateral stud 30 formed with a thread-guiding aperture disposed adjacent the heel of the looper-blade. The shank portion is 20 formed at its lower end with a lateral flange from which depends the stud 31 by which it is secured upon the looper-carrier, and the blade portion is secured adjustably in position upon the shank 28 by means of a fastening screw 32 passing through an elongated aperture 33 of the extension and tapped into the portion 28.

The point of the looper-blade is laterally offset from alinement with the body portion, 35 as represented more particularly in Fig. 8, and its upper edge is formed with a thread groove 34 extending from the end of the heel forwardly and terminating in the convex face of the blade adjacent the aperture 40 35 at one end of a transverse guide aperture 35. The looper-blade with its extension is in practice struck up from a sheet metal blank in order to be cheaply constructed in various shapes and sizes that are required for different 45 stitching conditions, the different varieties of blade portion being interchangeable with a uniform pattern of shank portion. By this means, not only is the construction of the looper facilitated, but a machine fitted for one class of stitching may be readily 50 changed for other work and at a much smaller expense than with loopers of the ordinary construction in which the blade and shank are formed integral.

55 Each looper-shank stud is secured adjustably by means of a set-screw 36 within a socket in the cross member 37 of the looper-carrier 38 consisting of an upwardly extending arm provided with a perforated boss or sleeve 39 and with a lateral extension 40 terminating in a ball-stud 41. The sleeve 39 is adapted to rock and slide endwise upon the reduced portion 42 of a supporting fulcrum-pin disposed substantially parallel 60 65 with the main-shaft 5 and provided at the

opposite ends with the enlarged eccentrically disposed portions 43 and 44, the latter of which is secured removably to the body of the fulcrum-pin for convenience in assembling the parts and both of which are mounted in suitable bearings of the base 1, as indicated in Fig. 1.

The ball-stud 41 is embraced by a strap 45 of the pitman-lever 46 having at its opposite end the integral lower section 47 of a strap 75 having the cap section 48 and embracing the inclined looper-actuating crank 6, the axis of which is inclined to, but embraced within a plane parallel with and spaced from, the axis of the shaft 5, as will be clear from an 80 inspection of Figs. 5, 6 and 7. The strap sections 47 and 48 are provided with the perforated lugs 47' and 48' adapted to be secured together by means of the screws 49. These lugs are so placed that each of the 85 strap sections projects at one end beyond the other and into contact with one of the thrust flanges 50 disposed at the opposite ends of the inclined crank 6 and provided with laterally projecting rims 51 slightly 90 overhanging the crank 6 to afford a surrounding oil cavity whose walls may be slightly undercut for better retaining a supply of oil. The screw-receiving apertures of the lugs 48' are of elongated form so as 95 to provide for relative endwise adjustment of the strap sections to take up wear.

In the operation of the machine, the crank 6 constitutes an actuating element whose rotary movements are transmitted through the 100 member 46 acting as a pitman to the lateral arm 40 of the looper-carrier to impart rocking movements to the latter upon the fulcrum-pin 42; while said rotary movements are transmitted through said member 46 acting as a vibratory lever to impart bodily lateral movements to the looper-carrier endwise of the supporting fulcrum-pin 42. The resultant movement imparted by the actuating element 6 to the looper-carrier mounted 105 and connected therewith as described is such as to cause the looper points to traverse elliptical paths substantially such as that shown in dotted lines in Fig. 11. As represented in Figs. 6 and 7, the crank 6 is so 110 disposed that its axis is inclined relatively to the axis of shaft 5 and also is offset therefrom so that the axes of the shaft and the crank do not intersect, which causes the progressive sidewise movement of the 115 looper-carrier during its oscillatory movements in such manner as to cause the looper points to traverse elliptical paths whose axes are substantially parallel with the blades, and thus at an inclination with the 120 shaft 5 and the direction of feed, as represented diagrammatically in Fig. 11 in which the dotted ellipse designated *x* indicates the path of the looper point, the arrow *y* the direction of endwise movement of the looper 125 130

to seize a needle-thread loop and the arrow $\rightarrow$ the direction of feed of the work.

The cap section 48 of the pitman-lever strap has, upon its upper side and near the 5 end having the least circular travel under the action of the crank 6, a boss 52 formed with a transverse perforation in which is secured by means of the set-screw 53 one end of a laterally extending controller arm 54 10 whose upturned and flattened outer end portion 55 is shown provided with a plurality of thread-eyes 56 correspondingly with the number of loopers mounted in the looper-carrier. Secured upon the 15 looper-carrier intermediate its ends is a bent plate 57 formed with a single thread-eye 58. Mounted upon the bed-plate is a post 59 having at its upper end a transverse aperture in which is secured by means of the 20 set-screw 60 the end of a rod 61 whose upturned and flattened end 62 is formed with thread-eyes 63 preferably corresponding in number with those of the controller arm 54.

In threading up the machine, a lower 25 thread t for each looper is led from the source of supply through one of the several tension devices 64, and thence downwardly through one of the guide-loops 65 sustained by the rod 66 fixed in the lower portion of 30 the standard. It is thence led through one of the stationary thread-eyes 63 and the corresponding thread-eye 56 of the controller-arm 54 from which it is passed through the eyelet 58 sustained by the looper-carrier to 35 the apertured stud 30 at the heel of the looper from which it is passed through the guide-groove 34 and transverse aperture 35 of the looper-blade to the delivery aperture 25 in the point of the latter. It will be ob- 40 served that, owing to its position upon the strap section 48, the controller-arm 54 derives comparatively slight rising and falling movements from the crank 6, but that it receives lateral vibratory movements corre- 45 sponding in extent with those of the pitman- lever 46 although timed to be performed a quadrant earlier in the rotation of the crank.

The relative operative movements of the 50 thread-guiding elements 56 and 58 are such that the slack in the lower thread caused by the operative movements of the looper is taken up thereby in the production of each 55 controller arm 54 at such time is substantially in alinement with the thread-eyes 63 and 65, so as to impose a substantially direct pull upon the thread in each stitch-forming cycle in drawing off a supply for 60 the succeeding stitch.

Secured upon the forward eccentric portion 43 of the fulcrum-pin 42 by means of the set-screw 67 is the hollow boss 68 at one 65 end of the shift-lever 69 whose opposite end is provided with the lateral finger 70. The

inner face of the lever 69 is provided with a seat to which is secured by means of the screw 71 the segmental plate 72 whose inner face is flat excepting at one end which is formed with the recess 73. Mounted within 70 a bearing socket of the base 1 is a locking plug 74 shouldered to produce a reduced inner portion 75 whose extremity is adapted to enter a peripheral notch or recess 76 formed in the outer face of the adjacent 75 thrust flange 50 of the crank element 6. A spring 77 surrounding the reduced portion 75 of the plug 74 tends to maintain the latter in engagement with the segment-plate 72.

In the normal lateral and substantially 30 horizontal position of the lever 69, the fulcrum-pin 42 is in its proper relation with the main-shaft to insure the requisite operative movement of the loopers relatively to the needles in the performance of stitch-forming operations, and the tapered outer ex- 35 tremity of the locking plug 74 is seated within the recess 73 of the segment-plate 72 so as to permit the disengagement of the point of such plug from the thrust flange 50 90 for the free rotation of the shaft.

In all positions of the shaft 5 wherein the notch 76 is out of register with the plug 74, the flange 51 serves to lock the plug against endwise movement for retraction from the 95 recess 73, and hence the shift-lever 69 is effectually locked against movement. It is only at such time in which the plug 74 is in register with the notch 76 that the shift- 100 lever can be moved into the locking position 105 represented in the drawings, such movement serving not only to force the plug into locking relation with the flange 50 by ejection of the plug from the recess 73, but to turn the fulcrum-pin 42 upon the axis of its eccentric 110 portions 43 and 44 so as to lower the looper-carrier sleeve 39 relatively to the shaft 5 and actuating element 6. In the locking position of the shaft represented in the drawings, the loopers assume their most retracted 115 position relatively to the needles, and the shifting of the supporting fulcrum of the looper-carrier as described serves to impart to them an additional rocking movement upon the fulcrum-pin which communicates 120 to the loopers a further retractive movement which is of sufficient extent to expose the apertured extremities of the blades beneath the throat-plate for threading or other purposes. While the loopers are so retracted it 125 is evident that the main-shaft will be locked against turning, the unlocking being effected only at the completion of the movement of the shift-lever 69 into normal lateral position where the fulcrum-pin 42 is returned 130 to its normal relation with the main-shaft and the loopers are again in operative relation with the needles.

As shown in the drawings, the main-shaft is provided with the feed-actuating eccentric 130

78 embraced by a strap 79 provided with a transverse perforated boss 80 adapted to receive the sliding pin 81 mounted in the lateral arm 82 of the rocking frame sustained by the fulcrum-pin 83 and provided with upright arms 84 upon which is pivotally mounted by means of the pivotal pin 85 the feed-bar 86 to which is secured the feed-dog 87. The feed-bar 86 is formed with the inclined lateral arm 88 formed with a socket 89 to receive the slide-pin 90 which is provided with a strap 91 embracing the feed-lift eccentric 92 also secured upon the main-shaft. As will be observed, the eccentric 78 imparts to the feed-dog through the described connections operative movements at right angles to the main-shaft, while the eccentric 92 imparts the usual rising and falling movements to the feed-dog.

20 As represented in Figs. 1 and 2, above the base 1 is arranged a supporting frame-plate 93 having secured thereon the flat bar 94 formed with the tongue 95 extending lengthwise thereof to which is fitted the rearward portion of the throat-plate section 96 whose forward portion rests upon the upwardly extending lugs 97 of the frame-plate 93. The frame-plate is provided in its forward portion with depending bearing lugs 98 in which is mounted the rod 99 having adjustably secured thereto intermediate the lugs 97 the blocks 100 which are disposed below the looper paths and are formed with needle-guiding notches 101 to receive the pointed extremities of the needles 23.

25 Mounted within the head 4 of the bracket-arm is the usual presser-bar 102 having secured to its lower end the shank 103 of the compensating presser-foot which is shown provided with the independently movable foot-plates 104 opposed to the feed-dog.

30 The upper thread-handling means comprise the several tension devices 105 through which the several needle-threads *s* are led from the source of supply and thence through their respective guide-eyes 106 of the angular plate 107 secured to the arm 3 from which they are passed through their respective eyes 108 of the take-up arm 109 secured to and carried by the needle-bar link 17, over the rigid controlling arm 110 and through the guide-eyes 111 of the bent pin 112 secured in the top of the needle-bar to the respective needles.

35 In the operation of the machine, each needle descends and in its initial rising movement throws out its thread-loop which is entered by the point of its respective looper in the initial operative movement of the latter. During this looper movement, the looper-carrier guide-eye 58 moves outwardly and the controller-arm eyes 56 move inwardly relatively to the front end of the machine so as to approach alinement with the fixed thread-eye 63, thus giving up slack

in the lower thread to compensate for the advance of the looper.

The looper's substantially endwise movement causes the needle-thread loop to slip along its blade without unnecessary distension, the sidewise movement of the looper being only such as to permit the return of its blade upon the opposite side of the needle-path.

As the looper performs its retrograde movement, the thread-controlling elements 58 and 56 perform thread-drawing movements opposite to the thread-slackening movements previously described, thereby maintaining the lower thread taut between the looper point and the needle aperture of the throat-plate to insure the passage of the needle-point for a succeeding stitch between such strand of the lower thread and the needle-thread loop still embracing the looper-blade but drawn backwardly by friction with the latter. As soon as the needle-point has caught the looper-thread the movements of the thread-controlling elements 56 and 58 are such as to promptly slacken the lower thread so as to permit the proper setting of the previous stitch by the descent of the needle to its lowest position to draw up the needle-thread loop.

While the present improvement is well adapted to machines for producing a single line of stitching, it is particularly designed for machines employing a plurality of needles and coöperating loopers for forming simultaneously several parallel lines of stitching. Heretofore it has been customary to set the several needles in a line inclined to the direction of feed and to rock the coöperating loopers in planes at right angles with the direction of feed. By the arrangement described the looper-thread was led around the needle-blade in a substantially U-shaped bend or loop whose parallel limbs were embraced by the needle-thread loop, and the latter could be readily set upon the lower face of the fabric without undue strain upon the needle-thread.

Such arrangement of the stitch-forming mechanism had the serious disadvantage of beginning the parallel seams in a line at an oblique angle with the direction of feed, so that the seams would never begin nor end parallel with the extremities of the ordinary piece of work, making it necessary to have some of the seams terminate short of the extremity or others of the seams overrun the end of the work, which in certain cases was impracticable. According to the present improvement, the needles are arranged in a line at right angles to the direction of feed so as to overcome the objection referred to.

According to the present arrangement of the needles, if the looper-blades were disposed and reciprocated parallel with the di-

rection of feed, the looper-loop around the needle about to be drawn up by the embracing needle-thread loop would have the form of the letter V with its limbs spread wide 5 apart, so that the embracing needle-thread loop, which in practice extends partially around the needle-blade could only with difficulty be drawn up, and then only with a very tight tension which would endanger 10 the breaking of the thread. According to the present invention, the loopers are set with their blades at an angle with the direction of feed and receive simultaneous movements within-and crosswise of the direction of feed of such character that the resultant movements of the looper-blades are performed in substantially elliptical paths embracing the respective needles and having their axes inclined to the direction of feed 15 corresponding with the inclination of the blades. Thus the lead of the looper-thread around the needle-blade from the point of the retracted looper-blade is considerably to the side of the needle, so as to give the 20 looper-loop embracing the needle-blade a shape approximately that of the letter U, whereby the conditions for the stitch-setting action closely simulate those of the earlier construction before described.

30 By reference to Fig. 11 it will be observed that the movements of the looper crosswise of its blade are so gradual, excepting at the ends of its advance movements, as to be almost inappreciable, the loop-seizing movements being thus substantially endwise of the inclined looper-blade and the so-called "needle avoiding" movements transverse thereto or crosswise of the looper-blade.

As the forward portion of the looper-blade is laterally offset, it has been found objectionable to thread the lower thread along either face of the blade wherein it would contact with the needle-thread loop and resist to some extent the sliding movement of the latter along the blade. By providing the thread-housing groove 34 in the upper edge of the looper, the looper-thread is maintained between the limbs of the needle-thread loop, so as to be prevented from 45 injurious engagement with the latter throughout the stitch-forming cycle.

In the form of looper-blade represented in Fig. 12, the transverse thread apertures 25 and 35 are dispensed with, the top of the thread-groove 34 being closed adjacent the beak by a transverse pin 34', so that the lower thread t is led to the work directly from the forward end of such groove, and without 50 passing through the beak, as in the form 60 of looper represented in Figs. 8, 9 and 10.

In connection with the path of movement traversed by the looper point, the actuating element 6 will be found to act upon the looper-carrier in three distinct ways; viz., 65 (1) by reason of its radially offset position,

it acts as an ordinary crank in imparting endwise movement to the member 46 and thereby rocks the looper-carrier upon its fulcrum-pin, (2) by its inclination to the shaft 5 it causes the vibratory movement of 70 the member 46 to produce the normal side-wise or needle-avoiding movements of the looper-carrier, and (3) by its inclination combined with its offset and therefore non-intersecting relation with the shaft 5 it effects through the member 46 a supplemental endwise movement of the looper-carrier in advance of the described normal endwise movements which take place during the 75 rocking movements, whereby the normal elliptical path of movement resulting from the other two movements is inclined to the fulcrum-pin 42, and hence to the direction of feed at right angles thereto.

With different varieties of looper-blades 80 adapted for attachment interchangeably to shank portions of uniform shape and size, it is important that adjustment be provided in order that the point of the blade may be set at the proper distance from the needle 85 when in retracted position, and such adjustment is provided by the tongue-and-groove connection of the parts in conjunction with the fastening screw 32; while the cylindrical form of the stud-pin 31 permits a sidewise 90 adjustment of the looper-blade upon the carrier to accommodate needles of different 95 thickness or changes in the stitching conditions in other respects.

From the foregoing description, it is evident that the present improvement is susceptible of material modification in the construction and arrangement of its parts within the scope of the present invention, and that certain features characteristic of some 100 of the component parts may be omitted without departure from the invention.

Having thus set forth the nature of the invention, what I claim herein is:—

1. In a sewing machine the combination 110 with a work-support, an actuating shaft, and feeding mechanism, of stitch-forming mechanism comprising a reciprocating needle, a looper supported for movement transversely of the plane of the work-support with its 115 blade arranged at an acute angle with the direction of feed and means including an eccentric element on the actuating shaft for imparting to said looper endwise and side-wise movements in a substantially elliptical 120 path having its axis inclined to the direction of feed.

2. In a sewing machine, the combination 125 with a work-support and feeding mechanism, of stitch-forming mechanism comprising a reciprocating needle, a looper-carrier movable relatively to its supporting element in different directions in angular relation with each other, a looper sustained by said carrier, and means connected with said car- 130

- rier for imparting to the looper operative movements transversely of the work-support and in a substantially elliptical path having its axes inclined to the direction of feed.
5. 3. In a sewing machine, the combination with a work-support and feeding mechanism, of stitch-forming mechanism including a looper-carrier mounted to oscillate transversely of the work-support and upon 10 an axis at right angles with the direction of feed, a looper sustained by said carrier with its blade inclined to the direction of feed, and actuating means connected with said carrier and adapted to impart to the looper 15 operative movements in a substantially elliptical path having its axis inclined to the direction of feed.
4. A sewing machine looper mechanism comprising an endwise and sidewise movable 20 looper, a carrier therefor, an actuating shaft provided with an inclined crank having its axis in non-intersecting relation with that of said shaft, and an operative connection between said crank and looper-carrier.
- 25 5. A sewing machine looper mechanism comprising a looper, a carrier therefor, a supporting fulcrum providing a fixed axis for said carrier upon which it is adapted to perform both rocking and bodily lateral movements, an actuating shaft provided 30 with an inclined crank, and a pitman-lever having a strap embracing said crank and a pivotal connection with said carrier eccentric to said supporting fulcrum.
- 35 6. A sewing machine looper mechanism comprising a looper, a carrier therefor, a fixed supporting fulcrum for said carrier relative to which it is adapted to perform both rocking and bodily lateral movements, an actuating shaft provided with an inclined crank, and a pitman-lever having a strap embracing said crank and a pivotal connection with said carrier adjustable toward and from said supporting fulcrum.
- 45 7. A sewing machine looper mechanism comprising a looper, a carrier therefor, a support upon which said carrier has rocking and bodily lateral movements upon a fixed axis, an actuating shaft provided with 50 an inclined crank, and a pitman-lever having a strap embracing said crank and a pivotal connection with said carrier eccentric to said axis of movement.
8. In a sewing machine, the combination 55 with a work-plate and feeding mechanism, of stitch-forming mechanism comprising a plurality of reciprocating needles arranged in a line perpendicular to the direction of feed, a plurality of loopers each movable transversely of the work-plate and coöperating with one of said needles and having its blade arranged at an acute angle with the direction of feed, and actuating means for imparting to said loopers endwise 60 movements corresponding in direction with the looper-blades and sidewise movements, the combined movements being in a substantially elliptical path.
9. In a sewing machine, the combination with an actuating shaft, and feeding mechanism operating in a work-plate a direction crosswise of said shaft, of stitch-forming mechanism comprising a plurality of reciprocating needles arranged in a line parallel with said shaft, a plurality of loopers each movable transversely of the work-plate and coöperating with one of said needles and having its blade disposed at an inclination with said shaft, a carrier for said loopers, a supporting fulcrum upon which 75 said carrier is adapted to oscillate and slide, and means connected with said shaft for imparting to the looper-carrier compound oscillatory and sliding movements which are mainly in the direction in which the looper-blades extend.
10. A sewing machine looper mechanism comprising a looper, a carrier therefor, a supporting fulcrum for said carrier relative to which it is adapted to perform rocking and endwise movements, an actuating shaft provided with an inclined crank having thrust flanges at the opposite ends, and a pitman-lever having a pivotal connection with said carrier eccentric to the supporting 90 fulcrum and a strap embracing said crank and formed in two separable parts each projecting endwise beyond the other at one end and adapted to rest against the adjacent thrust flange of said crank.
- 100 11. A sewing machine looper mechanism comprising a looper, a carrier therefor, a supporting fulcrum for said carrier relative to which it is adapted to perform both rocking and endwise movements, an actuating shaft provided with an inclined crank having at the opposite ends thrust flanges with rims overhanging said crank, and a pitman-lever having a pivotal connection with said carrier eccentric to the supporting 95 fulcrum and a strap embracing said crank and formed in two separable parts each projecting endwise beyond the other at one end and adapted to rest against the adjacent thrust flange of said crank.
- 110 12. A sewing machine looper mechanism comprising a looper, a carrier therefor, a supporting fulcrum upon which said carrier is adapted to perform rocking movements, an actuating shaft and a rotary actuating element thereon for said looper, an operative connection between said element and said carrier, and means operative independently of said actuating shaft for shifting said supporting fulcrum toward and from 120 125 said actuating element.
13. A sewing machine looper mechanism comprising a looper, a carrier therefor, a

- supporting fulcrum for said carrier relative to which it is adapted to perform both rocking and endwise movements, an actuating shaft provided with an inclined crank, a pitman-lever having a strap embracing said crank and a pivotal connection with said carrier eccentric to said supporting fulcrum, and means for shifting said supporting fulcrum toward and from said shaft.
14. In a sewing machine, in combination, a looper movable endwise to seize a needle-loop and sidewise to position a loop for subsequent entry by the needle, a carrier for said looper, an actuating shaft provided with a crank having its axis inclined to, but embraced within a plane parallel with and spaced from, the axis of said shaft, and an operative connection between said crank and the looper-carrier from which the latter derives its movements in different directions.
15. In a sewing machine, in combination, a looper, a carrier therefor, a support upon which said carrier is mounted to slide and oscillate, an actuating shaft provided with a crank having its axis inclined to, but embraced within a plane parallel with and spaced from, the axis of said shaft, and an operative connection between said crank and the looper-carrier for imparting to the latter oscillatory and sliding movements.
16. In a sewing machine, in combination, a looper, an oscillating and sliding carrier therefor provided with a crank-arm, a pivotal support upon which said carrier is slidingly mounted, an actuating shaft provided with a crank having its axis inclined to, but embraced within a plane parallel with and spaced from, the axis of said shaft, and a sleeve embracing said crank and provided with a rigid arm, operatively connected with the crank-arm of said looper-carrier.
17. In a sewing machine, in combination, a shaft provided with an actuating crank inclined to its axis, a crank-follower journaled on said actuating crank, a pivotal pin mounted upon a fixed support substantially parallel with said shaft, a looper-carrier mounted for oscillation upon and reciprocation lengthwise of said pin and provided with a crank-arm operatively connected with said crank-follower from which said carrier derives said movements, and a looper mounted on said carrier.
18. A sewing machine looper mechanism comprising a looper, a carrier therefor, a supporting fulcrum upon which said carrier is adapted to perform rocking movements, a rotary actuating element for said looper, an operative connection between said element and the said carrier, shifting means for retracting and returning said supporting fulcrum from and into normal operative relation with said actuating element, and means for locking said actuating element against turning while the fulcrum is out of normal relation therewith.
19. A sewing machine looper mechanism comprising a looper, a carrier therefor, a supporting fulcrum upon which said carrier is adapted to perform rocking movements, a rotary actuating element for said looper, an operative connection between said element and said carrier, shifting means for retracting and returning said supporting fulcrum from and into normal operative relation with said actuating element, and means operatively connected with and actuated by said shifting means for locking said actuating element against turning while the fulcrum is out of normal relation therewith.
20. In a sewing machine, in combination, a looper mechanism comprising a looper, a carrier therefor, a supporting fulcrum for said carrier, an actuating shaft provided with an inclined crank, and a pitman-lever having a strap embracing said crank and a pivotal connection with said carrier eccentric to said supporting fulcrum, and thread-controlling means comprising a guide-eye upon the looper-carrier, an eyed controller-arm carried by the strap of said pitman-lever.
21. In a sewing machine, in combination, a looper mechanism comprising a looper, a carrier therefor, a supporting fulcrum for said carrier, an actuating shaft provided with an inclined crank, and a pitman-lever having a strap embracing said crank and a pivotal connection with said carrier eccentric to said supporting fulcrum, and thread-controlling means comprising a guide-eye upon the looper-carrier, an eyed controller-arm carried by the strap of said pitman-lever, and a fixed guide-eye disposed intermediate the source of thread supply and said controller-arm and from which the thread is led to the controller-arm in a direction lengthwise of said shaft.
22. In a sewing machine, in combination, a looper mechanism comprising a looper, a carrier therefor, a supporting fulcrum for said carrier, an actuating shaft provided with an inclined crank, and a pitman-lever having a strap embracing said crank and a pivotal connection with said carrier eccentric to said supporting fulcrum, and thread-controlling means comprising a guide-eye upon the looper-carrier, and a laterally extending eyed controller arm sustained upon the end of the pitman-lever strap nearest the axis of said shaft.
23. In a sewing machine, in combination, a looper mechanism comprising a looper, a carrier therefor, a supporting fulcrum for said carrier, an actuating shaft provided with an inclined crank, and a pitman-lever

- having a strap embracing said crank and a pivotal connection with said carrier eccentric to said supporting fulcrum, and thread-controlling means comprising a guide-eye upon 5 the looper-carrier, an eyed controller-arm carried by the strap of said pitman-lever, and means independent of said shaft for retracting said looper-carrier from operative relation with the needle.
- 10 24. A sewing machine looper mechanism comprising, a looper, a carrier therefor, a supporting fulcrum upon which said carrier is adapted to perform rocking movements, an actuating shaft, permanent operative 15 connection between said shaft and carrier, and means for retracting said carrier from normal operative position in a direction transverse to the axis of said fulcrum.
25. In combination, a looper-carrier, a 20 looper, a looper-blade, means for securing the looper upon said carrier in different angular relations therewith, and means whereby the looper-blade may be adjusted lengthwise relatively to said carrier independently 25 of said securing means.
26. A sewing machine looper comprising shank and blade portions separable from each other, and means for securing them together.
- 30 27. A sewing machine looper comprising a shank portion provided with a thread-eye, an eye-pointed blade portion separable therefrom, and means for securing them together.
28. A sewing machine looper comprising 35 a shank portion, a blade portion, and means for securing the blade portion adjustably lengthwise of the blade upon the shank portion.
29. A sewing machine looper comprising 40 a shank portion provided with a thread-eye and with a transverse tongue, an eye-pointed blade portion having a channel fitted to said tongue of the shank portion, and means for securing said portions together adjustably 45 lengthwise of said tongue.
30. A sewing machine looper comprising a shank portion and a blade separable therefrom, and of substantially flat cross-section and provided in one edge with a longitudinally extending thread-housing groove terminating in the side-face of the beak from 50 which the thread is delivered.
31. A sewing machine looper comprising a shank portion and an eye-pointed blade separable therefrom with the pointed extremity laterally offset, said blade being formed in its upper edge with a thread-groove terminating in the convex face adjacent said eye in a transverse threading aperture.
32. A sewing machine comprising, in combination, a frame, a work-support, a reciprocating needle, an oscillating looper, actuating means for imparting reciprocatory movements to said needle and loop seizing and sidewise movements to said looper, shiftable means for locking said actuating means, and means carried by said frame and operatively connected with said shiftable means for shifting said looper to a position for convenience in threading.
33. In a sewing machine, a frame, in combination, a main-shaft, a reciprocating needle, a movable looper coöperating with said needle, a pivoted looper-support, actuating 75 connections between said main-shaft and said looper support, means whereby said looper support may be moved from normal to abnormal position, shiftable means for so moving said looper support, and connections between said shiftable means and said main-shaft acting to lock the latter against rotation when said looper support is moved to abnormal position.
- In testimony whereof, I have signed my 85 name to this specification, in the presence of two subscribing witnesses.
- ALBERT HARRISON DE VOE.
